SPRING WAGON BOLSTER.
APPLICATION FILED OCT. 25, 1907.

2 SHEETS—SHEET 2.

UNITED STATES PATENT OFFICE.

JOHN LINIUS HAGEL AND AUGUST HAGEL, OF PROVIDENCE, MINNESOTA.

SPRING WAGON-BOLSTER.

No. 896,105.

Specification of Letters Patent.

Patented Aug. 18, 1908.

Application filed October 25, 1907. Serial No. 399,170.

To all whom it may concern:

Be it known that we, JOHN LINIUS HAGEL and AUGUST HAGEL, citizens of the United States, residing at Providence, in the county 5 of Lac qui Parle and State of Minnesota, have invented certain new and useful Improvements in Spring Wagon-Bolsters; and we do hereby declare the following to be a full, clear, and exact description of the invention, such as will enable others skilled in 10 the art to which it appertains to make and use the same.

Our invention has for its object to provide an improved spring wagon bolster which is, 15 nevertheless, adapted for general use on various kinds of vehicles.

To the above ends the invention consists of the novel devices and combinations of devices hereinafter described and defined in the 20 claims.

This improved bolster is made up of what, for distinction, may be designated as a lower or primary bolster and an upper or secondary bolster, and a novel arrangement of springs 25 whereby the latter is supported from the former. In some instances, usually in rear bolsters, the primary and secondary bolsters are connected by equalizing bars of novel construction and arrangement which hold 30 the two bolsters always parallel to each other, and this constitutes another feature of our invention.

The invention also involves other novel but minor features of construction, all of 35 which will be hereinafter described and defined in the claims.

In the accompanying drawings which illustrate the invention, like characters indicate like parts throughout the several views.

40 Referring to the drawings, Figure 1 is a view in elevation, showing the improved spring bolster as an entirety. Fig. 2 is a vertical longitudinal section, taken through the bolster approximately on the line $x^2 x^2$ of Fig. 3. Fig. 3 is a horizontal section taken approximately on the line $x^3 x^3$ of Fig. 1. Fig. 4 is an end elevation of the bolster, with some parts broken away; and Fig. 5 is a

transverse vertical section taken on the line $x^5 x^5$ of Fig. 1.

The so-called primary or lower bolster is made up of a pair of angle iron bars 1, the horizontal flanges of which are turned inward and are rigidly secured, preferably to tie plates 2, while the vertical flanges thereof are set outward or away from each other. The secondary or upper bolster is made up of a pair of similar angle iron bars 3, the horizontal flanges of which are turned outward and the vertical flanges of which are set 60 inward, approximately in vertical planes of the inner edges of the horizontal in-turned flanges of the lower angle bars 1. Near their outer ends, these angle bars 3 are rigidly secured together by split and out-turned lower 65 end portions 4 of tubular metal posts 5. Metal braces 6 that are riveted or otherwise rigidly secured at their upper ends to the outer sides of the hollow posts 5 are connected at their lower ends to the outer ends 70 of the angle bars 3, preferably by nutted bolts 7 that further assist in rigidly securing together the outer ends of the said angle bars 3.

The secondary or upper bolster is supported from the upper or primary bolster by a pair of double elliptical springs, each of which springs is made up of a pair of semi-elliptical springs 8, intermediately secured back to back, as best shown in Fig. 1. The 80 upper semi-elliptical springs 8, at one end, are connected by bolts 9 and 12 to brackets 10, rigidly secured to the overlying horizontal flanges of the corresponding upper angle bars 3, and at their other ends they work slidably 85 against the base flanges of brackets 11 that are rigidly secured to the respective angle bars 3 and through which and the vertical flanges of said angle bars the bolts 9 and 12 are passed to assist in holding the free ends 90 of said upper springs 8 against displacement. The lower elliptical springs 8 are connected, at one end, by bolts 13 to brackets 14 that are rigidly secured to the underlying lower angle bars 1, and the other ends of said springs work 95 slidably against the base flanges of brackets

15 that are rigidly secured to the respective angle bars 1. As shown, bolts 16 are passed through the vertical flanges of the angle bars 1, through spacing sleeves 17 and through vertical flanges of the brackets 15, to assist in holding the free ends of the lower springs 8 against displacement. By reference to Fig. 3 it will be noted that one of the lower semi-elliptical springs 8 is pivoted at one side of the center of the bolster, while the other lower semi-elliptical spring is pivoted at the other side of the bolster. The same statement is true in respect to the pivotal connection of the upper semi-elliptical springs to the upper angle bars 3. This equalizes the endwise thrust due to friction on the upper and lower bolsters under compression of the springs.

With the arrangement above described, 20 the springs keep compressed until the angle bars of the upper and lower bolsters are forced into the same or approximately the same vertical space. This is made possible by the reverse arrangements of the upper 25 and lower angle bars, so that their vertical flanges may overlap when the springs are compressed. This construction, as is evident, gives a complete spring bolster that occupies but very little vertical space and, 30 hence, does not necessitate the elevation of the wagon box or the supporting thereof in a position objectionably high above the axles.

In Figs. 4 and 5, the spring bolster is shown as supported on an axle 18 and connected thereto by nutted bolts 19 passed through the said axle and through the tie plates 2.

The tubular posts 5 serve also as sockets into which wooden posts or extensions may be inserted to increase the height of the 45 bolster posts, as required in a good many instances.

The wagon box will, of course, be supported directly upon the angle bars 3 of the upper or secondary bolster held between the posts 45 5. These posts 5, it is therefore evident, do not tend to move or slide in respect to the box and, hence do not wear the box.

The bolster described is substantially the form it will usually be used at the front of a wagon box. As already indicated, the bolster used at the rear of the wagon box is provided with an equalizer. This equalizer, as illustrated in the drawings and as preferably constructed, comprises a pair of transversely 55 crossed metal bars 20 that are intermediate connected for pivotal and limited sliding movements by a headed stud 21 secured to one of said bars and working in a slot 22 in the other bar. To reduce friction, a small roller 23 is shown as placed on the stud 21. These two equalizing bars are placed in the space between the front and rear angle bars 60 of the primary and secondary bolster. The

lower ends of said equalizing bars are connected to the lower ends of short links 24, the upper ends of which are pivotally connected at 25 to up-turned, inwardly and down-turned bent portions 26 of the lower angle bars 1. The upper ends of said equalizing bars 20 are pivotally connected by the intermediate portion of the bolts 9 and 12 to the vertical flanges of the angle bars 3 of the upper or secondary bolster.

As is usual, crossed equalizing bars 20 will hold the bars of the upper and lower bolsters 75 always parallel to each other but will permit the free vertical movements of the one in respect to the other.

What we claim is:

1. The combination with upper and lower 80 bolsters formed of angle irons having their vertical flanges reversely disposed so that they are adapted to overlap, of resilient means supporting said upper bolster from said lower bolster, substantially as described.

2. The combination with upper and lower bolsters, each formed from a pair of angle irons having their vertical flanges reversely disposed so that they are adapted to overlap, 90 of double semi-elliptical springs interposed between the horizontal flanges of said angle irons and yieldingly supporting said upper bolster from said lower bolster, substantially as described.

3. The combination with upper and lower bolsters, formed from pairs of angle irons having their vertical flanges reversely disposed so that they are adapted to overlap, of a pair of double semi-elliptical springs interposed between the vertically aligned horizontal flanges of the angle irons of said upper and lower bolsters and yieldingly supporting said upper bolster from said lower bolster, substantially as described.

4. The combination with a lower bolster made up of a pair of angle bars 1, having their flanges set outward, of an upper bolster made up of a pair of angle bars 3 having their flanges set inward, of springs interposed between the overlying horizontal flanges of said upper angle bars 3, and the underlying horizontal flanges of said lower angle bars 1, substantially as described.

5. The combination with a lower bolster 115 made up of angle bars 1 having their vertical flanges set outward, of an upper bolster made up of angle bars 3 having their vertical flanges set inward, double semi-elliptical springs interposed between the overlying horizontal 120 flanges of said upper angle bars 3 and the underlying horizontal flanges of said lower angle bars 1, and end posts rigidly secured at their lower ends to the end portions of said upper angle bars 3, substantially as described.

6. The combination with upper and lower bolsters, each made up of a pair of laterally spaced bars, of springs interposed between the vertically alined bars of said upper and lower bolsters, and a pair of transversely crossed intermediately pivoted equalizing levers, located between the laterally spaced bars of said upper and lower bolsters with their upper ends connected to said upper bolster and with their lower ends connected to said lower bolster, substantially as described.

In testimony whereof we affix our signatures in presence of two witnesses.
